OVERHEAD DOOR CONSTRUCTION

Alvin V. Rowe, Galesburg, Ill., assignor to Rowe
Manufacturing Company, Galesburg, Ill., a cor-
poration of Illinois

Application August 3, 1929. Serial No. 383,302

10 Claims. (Cl. 20—20)

My invention relates to overhead door constructions and particularly to improvements in overhead door constructions of the type disclosed in the copending application of Douglas A. Wilson, Serial No. 383,301, filed August 3, 1929.

In the above mentioned copending application an overhead door construction is disclosed in which a plurality of door panels are adapted to be shifted in a very expeditious manner from one position to another and it is an object of my present invention to provide improved means whereby door panels of the type set forth in that application may be effectively clamped against the door jamb when said panels have assumed their vertical position.

More specifically, my present invention contemplates the provision of a simple and durable actuating mechanism which is operable to shift the vertical sections of the guide rails so as to positively effect the clamping of the door panels against the door jamb.

In addition to the provision of effective means for sealing the door panels in position against the door jamb, it is an object of my present invention to provide, in combination with mechanisms for actuating said panels, a construction which will insure the sealing of the abutting edges of adjacently positioned panels.

More specifically it is an object of my present invention to provide improved hinge constructions between said panels which will enable companion overlapping edge portions of said panels to be effectively clamped together when the panels assume their vertical door closing position.

A still further object of my present invention is to provide interlocking door panels with hinge members which are adapted to support rollers in spaced relation with respect to the inner surface of said panels, said rollers being adapted to operate in vertical guide rails of the fixed or shiftable type, the hinge constructions being such as to insure a sealed interlocking abutment between the companion edges of the door panels.

These and numerous other objects and advantages will appear from the following detailed description when considered in connection with the accompanying drawings, wherein:

Figure 1 is a rear elevational view of an overhead door construction equipped in accordance with the teachings of my invention, said view being taken substantially along the line 1—1 of Figure 4;

Figure 2 is an enlarged detailed side elevational view of abutting portions of the door panel, said panels being shown in closed relation;

Figure 3 is a view similar to Figure 2 disclosing said panels in open position;

Figure 4 is an enlarged fragmentary vertical sectional view taken substantially along the line 4—4 of Figure 1;

Figure 5 is a side elevational view taken from the opposite side of the structure shown in Figure 4;

Figure 6 is a view of the upper section of the structure of Figure 5 disclosing the door panels in partially closed position;

Figure 7 is an enlarged transverse sectional view of the vertical guide rail and support therefor taken substantially along the line 7—7 of Figure 6; and

Figure 8 is an enlarged fragmentary side elevational view of the upper portion of the mechanism for shifting the vertical guide rail, said shifting mechanism being shown in unclamped position.

Referring now to the drawings more in detail wherein like numerals have been employed to designate similar parts throughout the various figures, it will be observed in Figures 1 to 8 inclusive that my invention contemplates the provision of an overhead door construction having guide rails denoted generally by the numeral 20, said guide rails consisting of an upper section 22 and a lower or vertical section 24. This upper section 22 is secured in a fixed position to the garage overhead structure in any suitable manner not shown, the forward or curved portion of the guide rails being secured to a plate 26 and a support 28 extending outwardly from the door jamb 30, Figures 4 to 6 inclusive. The lower vertical guide rail 24 is supported by a plurality of spaced supports 32, 34 and 36. These supports 36 comprise a U-shaped section 38 which is secured to the door jamb in any suitable manner and a section 40 which is provided with a curved slot 42 for receiving a supporting bolt 44 which is secured to the guide rail 24 as clearly shown in Figure 7. The curved section 46 of the guide rail is adapted to abut a flange 48 which is co-extensive with the section 40 when the guide rail is moved rearwardly to the position disclosed in Figures 6, 7 and 8.

A mechanism is provided in association with each vertical guide rail 24 for causing said guide rail to be moved toward or away from the door jamb 30 and this mechanism includes a T-shaped lever 50 which is pivoted to the section 40 of the support 32 at 52. The lower extremity of the cross arm of said T-lever is secured to the bolt 44 while the upper extremity is secured to one

end of a coiled spring 54 which spring is suitably secured at its opposite extremity to the door jamb 30. This T-lever 50 is operatively connected with an L-shaped lever 56 by means of a vertical link 58. This L-shaped lever 56 is pivoted at 60 to the support 36 and is secured to the bolt 44 associated with said support. From the foregoing it will be understood that when the link 58 is moved downwardly so as to cause the lever 50 and the lever 56 to occupy the position shown in Figures 4 and 5, the guide rail 24 will be moved forwardly toward the door jamb and when the link 58 is moved upwardly so as to bring the levers 50 and 56 to the position shown in Figures 6 and 8, said rail sections will be moved away from the door jamb.

The downward movement of the levers 50 and 56 is occasioned in response to the engagement of a pin 62, Figures 4 and 5, with each of the levers 50. These pins 62 are carried by a connecting member 64 which forms the connecting medium between a carriage device indicated generally by the numeral 66 and a pin 68 which passes through hinge members 70. These hinge members 70 serve to connect an upper door panel 72 with the next adjacent door panel 74. Similar hinge members serve to connect the door panel 74 with a panel 76 and this panel 76 is also hinged in a similar manner to the lowermost panel 78. Associated with and supported adjacent each of the hinge devices 70 are rollers 80 which are guided within the rails 22 and 24. The axes of these rollers are equally spaced from the inner surfaces of their companion door sections and it will thus be apparent that when the guide rails 24 are moved toward the door jamb in the manner described above, the door panels will be tightly clamped against said door jambs.

As stated above, I employ a carriage mechanism 66 which is adapted to cause the uppermost panel to be tightly clamped against the door jamb when said panels occupy the positions shown in Figures 1 and 4. For a detailed description of this mechanism 66 attention is directed to the aforementioned copending application of Douglas A. Wilson in which this device is described in detail. It will suffice for an adequate understanding of the present invention to state that this carriage mechanism includes a rocker arm 82 which is pivotally mounted upon a pin 84 and this pin 84 is carried by a plate 86. The plate 86 also supports a roller 88 which rides along the outer flat surface of the guide rail 22. In order to effect the raising of the door panels I employ suitable lifting chains which I have designated by dot and dash lines 90, Figures 1 and 4.

The hinge members 70 are disclosed in detail in Figures 2, 3 and 12 and it will be noted that these hinges include a plate section 92 secured to their companion door panel and angularly disposed ears 94 which extend outwardly from the inner surface of the door panels. The arrangement of the hinges is such as to expedite the positive interlocking engagement between the adjacent edges of the panels. These edges are provided with notches 96 which are designed to receive companion projections 98 in the manner shown in Figures 2 and 3, thereby presenting a ship-lap joint. By having the axis of the hinge spaced from the inner surface of the door panels I am able to obtain the proper swinging movement of said panels so as to bring the adjacent edges thereof into proper positions of abutment. It will thus be apparent that my improved means

for positively effecting the clamping of the panels against the door jamb co-operates with the hinges 70 to effectively seal the panels in closed position.

From the foregoing description it will be understood that my invention contemplates the use of the above described hinge construction in connection with movable or fixed vertical guide sections, said hinge constructions serving with equal effectiveness in each instance. When the described hinge structures are used in connection with the tapered rail section, it is only necessary to have the hinge arms so disposed that the proper variation in the displacement of the axes of the rollers 80 from the inner panel surfaces, is obtained. In connection with the shiftable vertical rail section, the distances of the axes of the rollers 80 from the inner surfaces of the panels are the same and hence there need be no variation in the size of the hinge arms 94 as is the case where the hinges are used in association with a tapered rail section. The described shiftable vertical rail sections serve to positively and tightly secure the door panels against the door jamb and this jamming action is entirely automatic by reason of the engagement of the pin 62 with the T-shaped levers 50 as already described. The coiled springs 54 operate to quickly release the levers 50 and 56 immediately upon the disengagement of the pin 62 from the lever 50. It will thus be apparent that my invention broadly contemplates the provision of an overhead door construction in which two sealing operations are simultaneously made, namely the sealing of the door panels against the door jamb and the sealing of one panel against the adjacent panel by reason of the above described ship-lap joint. As already set forth, the hinge structures co-operate to effectively cause the upper panels to be swung rearwardly and bring about a swinging movement between the panels so as to effect the proper opening and closing of the ship-lap joints. While I have preferred to disclose a specific rail shifting mechanism in connection with the devices shown in Figures 4 to 8 inclusive, it should be understood that other modifications might be employed to obtain the same result without departing from the spirit and scope of my present invention.

Having thus described my invention, what I claim as new and desire to secure by Letters Patent is:

1. In combination with a door opening of a garage or structure of like nature, an overhead door construction comprising a plurality of shiftable door panels for traversing said door opening, guide rails for directing said door panels from one position to another, said guide rails having a substantially vertical section which is movable toward and away from the door jambs, and a lever mechanism operable in response to the closing of the door panels to effect the shifting movement of said vertical rail sections toward the door jambs.

2. In combination with a door opening of a garage or structure of like nature, an overhead door construction comprising a plurality of shiftable door panels for traversing said door opening, guide rails for directing said door panels between closed and opened overhead positions, a vertical section of said guide rail being laterally shiftable, a mounting for said vertical rail section, and a lever mechanism pivoted upon said mounting and operable in response to the movement of the door panels for effecting the shifting of said vertical rail sections.

3. In combination with a door opening of a garage or structure of like nature, an overhead door construction comprising a plurality of shiftable door panels for traversing said door opening, guide rails for directing said door panels between closed and opened overhead positions, a vertical section of said rail being laterally shiftable, actuating means connected with said vertical rail sections, a panel controlling device mounted upon said rail sections for controlling the movement of the uppermost door panel, and means carried by said panel controlling device for engaging said actuating means to effect the shifting movement of said vertical rail section. 80
- 10 4. In combination with a door opening of a garage or structure of like nature, an overhead door construction comprising a plurality of shiftable door panels for traversing said door opening, guide rails for directing said door panels between closed and opened overhead positions, a vertical section of said rail being laterally shiftable, a plurality of lever mechanisms for shifting said vertical sections, and a link connecting said lever mechanisms. 85
- 15 5. In combination with a door opening of a garage or structure of like nature, an overhead door construction comprising a plurality of shiftable door panels for traversing said door opening, guide rails for directing said door panels between closed and opened overhead positions, an upright section of said guide rails being movable toward and away from the plane of the door opening, and a lever mechanism pivoted adjacent said upright rail section for effecting the movement thereof. 90
- 20 6. In an overhead door construction, a plurality of hingedly connected door members for traversing a door opening, said members being capable of shifting from a substantially vertical closed position to an overhead open position, and door sealing means including a vertically disposed laterally shiftable member and lever means operable in response to the shifting of the door members for causing the lateral movement of said vertically disposed member to thereby effect the sealing of all the door members with respect to the door opening. 95
- 25 7. In an overhead door construction, a plurality of hingedly connected door members for traversing a door opening, said members being capable of shifting from a substantially vertical closed position to an overhead open position, a door sealing means including a vertically disposed laterally shiftable means and a pivoted arm adapted to be shifted about its pivotal point as the door members approach their closed position for initiating the lateral movement of said vertically disposed laterally shiftable means whereby to effect the sealing of all the door members with respect to the door opening. 100
- 30 8. In an overhead door construction, a plurality of hingedly connected door members for traversing a door opening, said members being capable of shifting from a substantially vertical closed position to an overhead open position, a door sealing means including a vertically disposed laterally shiftable member at each side of the door opening and lever means at each side of the door structure and operable in response to the shifting of the door members for causing the lateral movement of said vertically disposed members to thereby effect the sealing of all the door members with respect to the door opening. 105
- 35 9. In an overhead door construction, a plurality of hingedly connected door members for traversing a door opening, said members being capable of shifting from a substantially vertical closed position to an overhead open position, a door sealing means including a vertically disposed laterally shiftable means and a pivoted arm adapted to be shifted about its pivotal point as the door members approach their closed position for initiating the lateral movement of said vertically disposed laterally shiftable means whereby to effect the sealing of all the door members with respect to the door opening. 110
- 40 10. In a door construction, a shiftable door member adapted to traverse the door opening, a vertically disposed laterally shiftable member positioned at each side of said door opening and adapted to traverse substantially the entire vertical height of the door member when said door member occupies its door closing position, and means shiftable with respect to said vertically disposed member and said door member in response to the movement of said door member when the door member approaches its door closing position to laterally shift said vertically disposed members whereby to effect the sealing of the door member with respect to the door opening. 115
- 45 120
- 50 125
